BLANK EJECTING MECHANISM

Howard F. Jordan, Beloit, Wis.

Application February 14, 1947, Serial No. 728,523

3 Claims. (Cl. 164—33)

1

My present invention relates generally to machines for punching metal sheets, and more specifically to an improved blank ejecting mechanism or knockout pin for use with a power operated vertically reciprocal punch press, with a selective and interchangeable use of wide variety.

The primary object of the invention is the provision of mechanism for ejecting the blank from the die of a punch press, which employs a positive impact ejector operating in a horizontal plane to eject the blank from the die and clear the die for a succeeding operation of the reciprocating punch; and means are provided for retarding the ejection until the punch has cleared the way for an ejection.

The ejecting mechanism consists in certain novel combinations and arrangements of parts including a spring actuated ejector and its cam controlled mechanism as will hereinafter be described and more specifically set forth in my appended claims.

The component parts of the ejecting mechanism may be manufactured with facility at comparatively low cost of production, and assembled conveniently to insure a reliable, durable, and efficient mechanism, readily adapted for use with a variety of vertically operating punch presses and similar power tools.

In the accompanying drawings I have illustrated a complete example of a physical embodiment of my invention in which the parts are combined and arranged in accord with one mode I have devised for the practical application of the principles of my invention. It will however, be understood that changes and alterations are contemplated and may be made in these exemplifying drawings and mechanical structures, within the scope of my claims without departing from the principles of the invention.

Figure 1 is a view in side elevation showing part of a punch press and die with which the ejector mechanism is combined and shown in position to retard or hold out the ejector for delayed action in knocking the blank from the die.

Figure 2 is a front elevation of the mechanism with the cam device uplifted.

Figure 3 is a top plan view of ejector mechanism.

Figure 4 is a view in side elevation with the ejector pin held in retracted position.

Figure 5 is a view partly in section and partly in elevation with the parts in position of Fig. 4.

Figure 6 is a fragmentary detail side elevation showing the co-action of the actuating cams and rollers for the ejector bolt or pin.

2

Figure 7 is a vertical sectional detail view at line 7—7 of Fig. 5.

The ejector mechanism as here includes a tubular base or cylindrical housing 1 having two attaching flanges 2, 2 that are counterbored for the bolts 3 that attach it to a supporting member, as the die shoe 4 of the vertically reciprocating cutting or punching machine, and the housing is provided with a large interior end bore 5 and a reduced open end bore 6, the latter having laterally spaced longitudinally extending slots 7 in its opposite walls.

A solid cylindrical, horizontally disposed knockout bolt or blank ejector 8 is mounted in the smaller bore 6 of the housing, and its enlarged head 9 is fitted with a reduced extension or pin 10 which is located in position to reciprocate horizontally, and on its working stroke to strike and eject the punched blank B from the die 4.

20 The ejector or knockout bolt is reciprocally mounted in the housing or cylindrical sleeve, and it is guided and stabilized in its movement by means of a stop pin 12, of cylindrical shape, that is passed through the lateral slots 7 of the housing and also through a transverse bore 13 of the ejector bolt 8.

25 On the opposite ends of the horizontally disposed stop pin and exterior of the housing 1 are journaled a pair of cam rollers 14, 14 which are retained against displacement by means of a resilient split ring or snap ring 15, and these split rings engage with annular grooves on the exterior surface of the stop pin adjacent its ends.

30 For plunging the ejector or knockout pin against the blank B, a large main spring 16 is located in the large bore 5 of the housing, coiled about the ejector bolt, and interposed between the head 9 and the annular wall or shoulder 17 of the housing, and a smaller spring 18 is coiled about the exposed end of the ejector bolt 8, interposed between the end wall of the housing and a snap ring 19 that is seated in an annular exterior groove at the end of the bolt.

35 In combination with the resiliently actuated plunger or ejector I have shown a vertically reciprocable punch holder 20 as part of the punch press and located above the ejector mechanism and in position for so-action therewith for setting and releasing the ejector, and a vertically arranged carrier 21 is fastened by screws 22 to the punch holder to travel therewith.

The carrier is provided with a pair of spaced wings or plates 23, 23, upon the exterior face of which wings is mounted a pair of vertically

spaced rivets 24 having enlarged retaining heads 25. These wings 23 project below the lower end of the body of the carrier 21, and their squared lower ends are cut off at 26 to form diagonal cam faces adapted to co-act with the rollers 14 of the ejector bolt.

A pair of loosely sliding guide plates or stop plates for temporarily holding the ejector as in Fig. 1 are mounted upon the side wings of the carrier, and these plates are slotted at 28; and 10 retained in sliding position by means of the heads 25 of the fixed rivets.

By this cam arrangement a delayed plunging action of the spring pressed ejector is attained and the ejector is held out until the blank B has been cleared by initial upward movement of the punch, and then by impact from the front pin of the ejector the blank is ejected from the die.

With the cams of the carrier in elevated position of Fig. 2, and as the punch holder and cam device descend on a punching stroke the carrier and guides initially straddle the housing. The straight bottom edges of the guide or holding plates, and the cam faces encounter the rollers and the slotted slide plates are instantaneously supported on the rollers as the cam device continues to descend.

In this continued downward movement of the carrier the rollers move the side plates 27 upward and the cams push against the rollers thus drawing the plunger outward and forcing the ejector bolt or plunger away from the die, and as the rollers move from under the guide plates, these free sliding plates fall in front of the rollers. On the initial upward movement of the carrier the cam moves from engagement with the rollers and the rollers engage the side faces of the guide plates as shown in Fig. 1 to hold the ejector against expansion of the main spring, thus preventing the ejecting movement of the bolt until the rollers are released by further upward movement of the plates 27.

On the first portion of the upstroke movement of the punch holder and carrier, the holding plates are thus lifted from in front of the rollers, the ejector is released, and the compressed main spring, by expansion, shoots or plunges the bolt to the left, and the impact pin strikes the blank B.

After this plunger movement of the ejector, the retracting spring 18, which is compressed on the ejecting stroke of the bolt, now expands and draws the plunger inward against the end of the main spring 16 so that the ejector is in position for a succeeding operation.

Having thus fully described my invention, what I claim as new and desire to secure by Letters Patent is:

1. In a horizontally disposed ejector mechanism for a vertically reciprocable punching machine, the combination with a fixed slotted housing and a spring-projected ejector bolt therein having a pair of rollers exterior of the slotted housing, of a vertically reciprocated carrier mounted over the ejector mechanism, said carrier having cam edges

for co-action with the rollers for setting the ejector, a pair of free vertically sliding holding plates mounted on the carrier and comprising substantially horizontal bottom edges and substantially vertical side edges for co-action with the rollers, and mounting means for the carrier whereby said plates maintain the setting of the ejector on initial stroke of the punch holder and are lifted with the carrier above said rollers during the upstroke of the punch holder.

2. In an ejector for a punching machine having a vertically reciprocating punch and holder therefor, the combination which comprises a housing having a slot therein mounted on the machine, an ejector slidably mounted in the housing, a spring positioned in the housing for actuating the ejector in the ejecting operation, a vertically reciprocating carrier having a beveled cam surface on the lower end thereof for resetting the ejector mounted on the punch holder and positioned to coact with the housing, a freely mounted vertically sliding holding plate mounted on the carrier and having a substantially horizontal bottom edge and a substantially vertical side edge positioned to coact with the ejector, and mounting means for the carrier whereby said plate maintains the setting of the ejector on the initial upstroke of the punch holder and is lifted with the carrier above the said ejector during the further upstroke of the punch holder.

3. In an ejector for a punching machine having a vertically reciprocating punch and holder therefor, the combination which comprises a housing having a slot therein mounted on the machine, an ejector slidably mounted in the housing, a spring positioned in the housing for actuating the ejector in the ejecting operation, a vertically reciprocating carrier having a beveled cam surface on the lower end thereof for resetting the ejector mounted on the punch holder and positioned to coact with the housing, a spring for retracting the ejector to its normal position, a freely mounted vertically sliding holding plate mounted on the carrier and having a substantially horizontal bottom edge and a substantially vertical side edge positioned to coact with the ejector, and mounting means for the carrier whereby said plate maintains the setting of the ejector on the initial upstroke of the punch holder and is lifted with the carrier above the said ejector during the further upstroke of the punch holder.
